TRACK LINER

John Clark, Walkerton, Ind.

Application May 12, 1947, Serial No. 747,472

3 Claims. (Cl. 254—43)

1

My invention relates to a railway track liner. An important object of the invention is to provide a track liner which will have a maximum holding action with the ballast, to prevent slipping of the liner during the operation.

A further object of the invention is to provide a track liner having a movable anchoring element or blade carried by the rail shifting bar or lever, which blade will properly coact with the ballast without previously forming a recess in the ballast to receive the blade.

A further object of the invention is to provide a track liner of the above mentioned character having a base of relatively large area which compresses the ballast beneath the base, due to the weight of the track carried by the base, and a ballast engaging anchoring element or blade which is movable into the ballast and compresses or crowds the ballast horizontally toward the compressed portion of the ballast beneath the base, thus effectively holding the liner against creeping in a direction opposite to that in which the track is to be shifted.

A further object of the invention is to provide a liner of the above mentioned character which is a self contained unit and is adapted for use with various types of jacks.

Other objects and advantages of the invention will be apparent during the course of the following description.

In the accompanying drawings, forming a part of this invention and in which like numerals are employed to designate like parts throughout the same,

Figure 1 is a perspective view of a track liner embodying my invention.

Figure 2 is a side elevation of the track liner arranged beneath the rail of the track, showing the swinging lever or bar in the horizontal starting position.

Figure 3 is a similar view showing the pivoted lever or bar in the inclined position for shifting the track the desired distance, and,

Figure 4 is a transverse section taken on line 4—4 of Figure 2.

In the drawings wherein for the purpose of illustration is shown a preferred embodiment of my invention a track liner is shown comprising a relatively large flat base 10. This base may be about eight inches wide and thirteen inches long, although these dimensions may be varied, as found advantageous. The base is continuous or imperforate to provide the maximum engagement with the ballast whereby the base will compress the layer of ballast beneath it, by virtue of the

2

fact that the base carries the load of the track, which is very heavy. At its outer end this base 10 carries an upwardly projecting flange or stop 11. Near its inner end the base 10 has a pair of vertical apertured knuckles 12, formed integral therewith.

Arranged above the base 10 is a vertically swinging lever or bar 13, provided between its end and near its longitudinal center with a depending apertured knuckle 14, integral therewith, and pivotally connected with the knuckles 12 by a pin 15. Formed integral with the lever or bar 13 and arranged above it is a web 16 projecting laterally beyond the lever 13, to engage with the base of the rail, for forming a contact having a suitable area.

Arranged at the inner end of the lever or bar 13 is a ballast engaging anchoring element or blade 17, having a large area. This blade may be eight inches long and six inches wide, although these dimensions may vary. This blade is preferably imperforate so that its relatively large surface is continuous. The blade has a lower sharp beveled edge 18, with its lower point disposed outwardly with respect to the track or next to the inner end of the base 10. The blade 17 is preferably formed integral with the lever or bar 13 which is positioned at the longitudinal center of the blade 17 and near its upper end. The blade 17 is arranged at an inclined angle with respect to the lever or bar 13, such as an angle of 25° from the perpendicular with respect to the lever 13, although this angle may be somewhat varied. The blade 17 is vertically inclined when the lever 13 is in the horizontal position and this blade extends from the base 10 toward the lower edge of the blade 17. The lever or bar 13 is provided at its outer end with a jack engaging yoke or socket 19, arranged beneath it, and preferably formed integral therewith.

The liner is adapted for use in connection with a lifting jack 20 of any well known or preferred type. This lifting jack may be of the ordinary track type, including a vertical housing 21 having a base or foot 22, which is placed upon the base 10 and also engages the flange or stop 11. This jack includes a vertically movable toe 23, which is raised and lowered by the usual manually operated means. This toe engages within the yoke 19.

The operation of the liner is as follows: When it is desired to shift or line the track to the right, Figures 2 and 3, the liner would be arranged beneath the left rail R and between a

pair of cross-ties. It is usually necessary to remove some of the ballast so that the implement may be inserted beneath the rail. The lever or bar 13 is in the approximate horizontal position, when starting the operation, and the anchoring blade 17 is vertically inclined, and extends to the right toward its lower sharp edge 18 or from the base 10. The jack 20 is applied to the base 10 and the toe 23 is moved into the yoke or socket 19. The liner is adjusted longitudinally so that the outer edge 24 of the rail base 25 is near the longitudinal center of the short arm of the lever, which short arm extends from the pivot 15 to the yoke 19. When the jack is operated to raise the toe 23, the lever or bar 13 is swung vertically upon its pivot, the short arm of this lever rising and moving to the right, Figure 3. As the short arm rises, the weight of the track is transmitted to the base 10, which causes the base to press down upon the ballast beneath it and form a layer of highly compressed ballast, the aggregates of which are not free to slip. While this downward pressure of the base 10 upon this ballast layer is occurring, the anchoring blade 17 is swinging downwardly and also moving horizontally outwardly with respect to the track or toward the base 10. Since the lower edge of the blade 17 is sharp, it will readily dig into the ballast and will not overcome the downward pressure upon the base 10, and will not materially reduce the compression of the ballast beneath this base 10. The blade 17 crowds or moves the ballast between it and the base 10 toward the base 10, and this ballast is pressed against the compressed layer ballast beneath the base 10. Hence the blade 17 acts against the ballast which it engages and since this ballast acts against the ballast compressed beneath the base 10, the blade 17 effectively holds the base 10 against creeping to the left, or in a direction from the track, which is a tendency caused by the pressure in that direction from the track. As the lever or bar 13 rises, the base 25 of the rail has its edge contacting with the web 16 at the point 24, and the web does not slide down the inclined lever 13 as it might be expected, but the base 25 and the entire adjacent section of the track is positively shifted to the right a slight distance, to line the track. The rail and cross-tie are slightly lifted, but the lifting is incidental and is slight as it is not desired that the ballast should get beneath the cross-ties and disrupt the level surface of the track. Since the blade 17 is inclined, at the starting operation, its horizontal moving or crowding of the ballast starts immediately. The inclination of the blade 17 also exerts a slight downward pressure upon the ballast which is continued until the blade is vertical. The lever 13 is ordinarily swung to the end of its travel by the time the blade 17 is moved downwardly to the vertical position or slightly past such vertical position. It is thus seen that when the lever 13 is inclined and is exerting the lateral pressure upon the base 25 of the rail to shift the track laterally to the right, the blade 17 will then be in the lowermost position and forced into the ballast, and pressing the ballast horizontally against the compressed ballast, beneath the base 10, whereby the base 10 cannot creep to the left.

It is to be understood that the form of my invention herewith shown and described is to be taken as a preferred example of the same and that various changes in the shape, size, and arrangement of parts may be referred to without

departing from the spirit of my invention or the scope of the subjoined claims.

Having thus described my invention, what I claim is:

- 5 1. A track liner, comprising an elongated relatively wide base having a substantially continuous ballast engaging surface, a lever extending longitudinally of the base and having both of its ends arranged at an elevation above the ballast in all operative positions, means to pivotally mount the lever upon the base with the pivot arranged nearer one end of the lever to provide short and long arms, the short arm of the lever terminating inwardly of one end of the base and the long arm projecting beyond the opposite end of the base, a relatively wide anchoring blade rigidly secured to the outer end of the long arm and extending laterally beyond the same and projecting downwardly therefrom, said blade being inclined longitudinally with respect to the long arm and arranged at an obtuse angle with respect thereto, and a stop mounted upon that end of the base projecting outwardly beyond the short arm of the lever for engagement with a jack to be mounted upon the base for moving the short arm of the lever, said pivot being arranged adjacent to the end of the base remote from said stop.
- 10 2. A track liner, comprising an elongated relatively wide base, a lever extending longitudinally of the base and having its ends arranged at an elevation above the ballast when the lever is in all operative positions for shifting the rail, means to pivotally mount the lever upon the base with the pivot arranged near one end of the base and nearer one end of the lever than the other end of the lever to provide short and long arms, the long arm projecting outwardly beyond the end of the base next to the pivot, the short arm terminating inwardly of the opposite end of the base, such opposite end having an upstanding stop, a relatively wide anchoring blade rigidly secured to the outer end of the long arm and extending laterally beyond the same and projecting downwardly therefrom said blade being inclined longitudinally with respect to the long arm and arranged at an obtuse angle with respect thereto, and a jack mounted upon the said opposite end of the base and engaging the stop, said jack having an operating element engaging the short arm of the lever.
- 15 3. A track liner, comprising an elongated relatively wide base, a lever extending longitudinally of the base and adapted to be substantially horizontally arranged in the starting position, one end of the lever extending outwardly beyond the corresponding end of the base and the opposite end of the lever terminating short of the opposite end of the base, means connecting the base and lever to pivotally mount the lever upon the base to swing in a substantially vertical plane, a socket forming element carried by said opposite end of the lever for receiving therein the toe of a jack which is mounted upon the end of the base extending outwardly beyond said opposite end of the lever, and a relatively wide anchoring blade bodily rigidly mounted upon the end of the lever projecting beyond the base and extending laterally beyond the arm and projecting below the arm, said blade being inclined longitudinally of the arm and arranged at substantially an obtuse angle with respect to the arm, the blade being in an upstanding position when the arm is substantially horizontal and
